HEAT EXCHANGERS OF THE INDIRECT PLATE PACK TYPE

Filed Feb. 27, 1961

Diagram illustrating a rectangular frame with a central opening and a diagonal line. The frame is divided into a grid of 12 equal squares. A central 2x2 square is open. A diagonal line starts from the top-left square of the central opening and extends to the bottom-right square of the frame. The line is solid in the first two squares and dashed in the remaining two squares of the frame. The number '5' is written to the right of the line, and the number '6' is written below the line.

Diagram showing a 5x3 grid of points. Vertices are labeled: top-left is 3, top-right is 2, bottom-left is 6, bottom-right is 5. A shaded region is shown in the bottom-right corner of the grid.

Diagram illustrating a 4x4 grid with numbered circles (1-8) and arrows (V, VI, VII, VIII) pointing to specific circles. A plus sign is placed between circles 7 and 8.

Diagram illustrating a 4x4 grid of circles. The circles are numbered as follows: top row (left to right) 3, 7, 1, 5; middle row 6, 2, 4, 8; bottom row 9, 10, 11, 12. A point labeled 'a' is located on the line segment connecting circle 3 to circle 6. A point labeled 'b' is located on the line segment connecting circle 9 to circle 11. Two arrows labeled 'IX' with a left-pointing arrowhead are positioned above the top row and below the bottom row.

HEAT EXCHANGERS OF THE INDIRECT
PLATE PACK TYPE

Sverre Knut Jنسن, Saltsjobaden, and Gustaf Conrad Egenwall, Stockholm, Sweden, assignors to Aktiebolaget Rosenblads Patentet, Stockholm, Sweden, a corporation of Sweden

Filed Feb. 27, 1961, Ser. No. 91,824

Claims priority, application Sweden Feb. 29, 1960

1 Claim. (Cl. 165—166)

This invention relates to heat exchangers of the indirect plate pack type in which plate-shaped heat transferring walls of thin plate material are arranged in packs with spaces between the walls serving as passages for heat exchanging fluids.

The main object of the invention is to provide a heat exchanger with a high heat transferring effect and great power of withstanding pressure at the same time as the heat exchanger is suitable for use with a heat exchanging fluid containing solid impurities such as fibres, sludge, etc.

The invention is mainly characterized by the combination of each wall at each side being provided with a large number of dimples forming corresponding bosses on the opposite side of the wall pressed out from the plate material so that at each side of the wall such dimples and bosses are alternatively distributed over the wall side surface, the bosses of the one wall in every second interspace between adjacent walls being positioned in spaced registering relationship to the dimples of the other wall and in the remaining interspaces between adjacent walls being positioned in abutting registering relationship to the bosses of the other wall and at least to a great number being welded together top against top.

The invention will now be described more in detail with reference to the accompanying drawing which diagrammatically and as an example illustrates an embodiment of a heat exchanger of the type to which the invention relates (FIGURES 1 to 3), as well as an embodiment of the invention applied to this heat exchanger (FIGS. 4 to 10). In the drawing:

FIG. 1 illustrates a side view of a heat exchanger of the cross current plate type;

FIGS. 2 and 3 illustrate the same heat exchanger in section on the lines II—II and III—III in FIG. 1;

FIG. 4 shows a central section IV of FIG. 1 of a heat transferring wall of a heat exchanger of the plate type on a larger scale;

FIG. 5 shows the same section as viewed in cross-section on the line V—V in FIG. 4, said line being the vertical central line of the wall;

FIGS. 6 and 7 illustrate the same section as viewed in cross-section on lines VI—VI and VII—VII, respectively, in FIG. 4;

FIG. 8 illustrates the central section IV in FIG. 1 of another heat transferring wall of the plate heat exchanger on the same scale as FIG. 4;

FIG. 9 illustrates the same section as FIG. 8 taken on line IX—IX in this figure, said line being the vertical central line of the wall, and

FIG. 10 shows the framed section X of FIG. 2 of the plate heat exchanger on the same scale as FIGS. 4 to 9.

Identical parts in the several figures are indicated with the same reference characters.

The heat exchanger 1 according to FIG. 1 consists of a pack of heat transferring walls 2 and 3 which are spaced by edge ribs 4. Every second space between the walls forms vertical passages 5 for one of the two heat exchanging fluids and the alternating spaces form horizontal passages 6 for the other fluid.

The walls which for the sake of clearness are shown with smooth surface in FIGS. 1 to 3 are provided with

2

pressings at least over the major portion of this surface. Walls 2 according to FIG. 4 and walls 3 according to FIG. 8 illustrate congruent sections IV of individual walls arranged in packs in registering positions, the registering centres of the corresponding surfaces of the walls being marked with “+.” The pressings consist of dimples 7 in both surfaces of the wall said dimples corresponding to boss-like pressings 8, likewise in both surfaces of the wall as most clearly shown in FIGS. 5 and 9 in which the neutral plane of the wall is indicated by a dash-and-dot line 9. In FIGS. 4 and 5 the bottoms of the dimples are indicated with small circles and the tops of the bosses with greater circles.

In the following description the surface *a* of the wall which in FIGURES 4 and 8 faces the viewer and which in FIGS. 5, 6, 7, 9 and 10 faces to the left will be referred to as the “*a*-surface” while the opposite surface *b* will be referred to as the “*b*-surface.” Walls which in the pack have their equally designated surfaces facing towards the same direction, for example to the right or to the left, respectively, according to FIG. 10 are called unidirected. Between unequally designated walls 2 and 3 respectively there is no difference other than that one wall of the equally designated surfaces *a* or *b* has bosses at the places where the other wall has dimples and vice versa as will be clear by a comparison of FIGS. 4 and 5 with FIGS. 8 and 9. In the unequally designated surfaces, however, the dimples and bosses are located at the same places on both walls as viewed in the plane of the drawing. Thus, if two unequally designated unidirected walls 3 and 2 are assembled so as to cover each other entirely (FIG. 4 over FIG. 8 or vice versa) their unequally designated surfaces will face one another and in these unequally designated surfaces the bosses of one surface will face the bosses of the other surface. If instead two equally designated walls 3 and 3 or 2 and 2 are assembled in the same manner (two FIGURES 4 or 8 being laid one over the other) the bosses of one of their unequally designated surfaces will face the dimples of the other surface.

According to the invention these different possibilities of distributing or assembling the walls in the pack are utilized in the following manner (see FIG. 10): Every second space 6 is formed between equally designated unidirected walls in which thus the bosses of one of the unequally designated surfaces face the dimples of the other side, said spaces (free spaces) in all places forming free passage of a heat exchanging fluid in meandering paths between said bosses and dimples. Every second free space is formed between one *a*-surface 2*a* and one *b*-surface 2*b* of two walls 2 while every second space is formed between one *a*-surface 3*a* and one *b*-surface 3*b* of two walls 3. The remaining spaces 5 are formed between unequally unidirected walls in which the unidirected bosses of the unequally designated surfaces—said bosses thus being oppositely directed—engage the tops of each other at which they are welded together by means of spot-weldings 10, said spaces (sealed or jointed spaces) forming passages for a second heat exchanging fluid in meandering paths around the bosses. Every second sealed or jointed space is formed between one *a*-surface 3*a* and one *b*-surface 2*b* of one wall 3 and one wall 2, and every second space is formed between one *a*-surface 2*a* and one *b*-surface 3*b* of one wall 2 and 3.

In this manner each of the jointed spaces will form a unit element which is capable of withstanding inner as well as outer pressure and which is suitable for conducting a heat exchanging fluid under pressure, for instance steam as heating medium, and not containing materials which stick to portions forming bridges across the space. The free spaces 6 are adapted for conducting media

containing such material, for example fibrous or sludge-containing liquids. Pressure in said spaces 6 in an apparatus according to FIGS. 1 to 3 will be effectively taken up by the outermost elements 5 at the both free ends of the pack said elements functioning as a jointed double wall of substantial rigidity. Of course, this fact does not prevent that it is possible in known manner to fix the pack between particular supporting walls at these ends so as to obtain a greater strength against the bursting action of pressure in the spaces 6. With such supporting walls or when such spaces are approximately free of pressure also the outermost spaces of the pack may consist of free spaces. The meandering passages which both types of spaces form, highly contribute to the turbulence and thus to a high heat transferring effect.

From a comparison between FIGS. 5, 6 and 7 of which the two last mentioned ones are cross-sections along the lines VI—VI and VII—VII of FIG. 4, respectively, it will be clear that the walls are vaulted or arched at all places except the small plane portions of the dimples and bosses. This shape results in a great rigidity of the wall and causes that the meandering bordering surfaces of the spaces throughout are free from corners or edges which could collect impurities.

The pattern according to which the pressings are distributed over the walls may be of any shape provided that the pattern is common for all walls. In the case illustrated in the drawing, however, this pattern has a special character resulting in particular advantages. A comparison between FIGS. 4 and 5 shows that if a wall according to FIG. 4 is turned 180° either in its plane around an axis transverse to the wall and passing through the centre of the wall or turned right about face around the central line V—V in the plane of the wall the appearance or image of the section IV will change from that shown in FIG. 4 to that shown in FIG. 8. This is due to the fact that (1) the distribution is such that on each surface of the wall for each boss there may be found a dimple on a straight imagined line drawn in the plane of the wall from the boss through the centre of the wall—said dimple lying on the opposite side of the centre at the same distance therefrom as the relevant boss whereby change of appearance or image is rendered possible by turning about the transverse axis, and that (2) the pattern of distribution is symmetrical in respect of the relevant central line so as to enable said change of appearance by turning about the centre line. Of course, only one of said conditions as regards the distribution need to be fulfilled in order to render a change of appearance or image possible by turning the wall. In this manner the walls indicated at 3 may be identical to the walls indicated at 2 but in the pack merely walls 3 are turned in relation to walls 2 in one or the other of the manners indicated above. In a pack assembled by such identical walls each free space 6 as clearly shown 55

in FIG. 10 will be formed between equally turned walls while each jointed space 5 will be formed between unequally turned walls, and more particularly, the equally turned walls forming every second free space are unequally turned in relation to the equally turned walls forming the remaining free spaces.

As an example of a type of plate heat exchangers of the type to which the invention relates we have selected a cross current apparatus with square walls because such an apparatus is most easy to illustrate clearly and is most simple to serve as the basis of a description of the invention. However, the application of the invention is not restricted to any determined type of plate heat exchanger. For example, the walls may be elongated and have contours of any shape and the apparatus may be constructed for counter current or parallel-flow. Only in the case where a pack of walls according to the invention is to consist of identical walls said contours should be such as to render it possible that also unequally turned walls as above may be assembled so as to cover one another entirely. The inlets and outlets for the heat exchanging media may consist of slots or gaps between the outer contours of the walls or of a series of apertures through the planes of the walls, etc.

What we claim is:

In a heat exchanger of the indirect plate type having a pack of heat transferring walls of thin plate material arranged in spaced face to face relation, the interspaces between the walls constituting passages for heat exchanging fluids, each such wall at each side being formed with a large number of dimples therein, the material of each such wall encompassing said dimples forming corresponding bosses on the opposite side of the wall extending out from the plate material so that at each side of each wall such dimples and bosses are alternatively distributed over the wall surface, said walls being assembled in said pack with the dimples and bosses of opposed plates bordering each interspace being positioned in different relationship to each other in different interspaces and in every second such interspace the bosses of the one wall extending into the interspace being in spaced registering relationship with respect to the dimples formed in the other wall bordering said interspace and in the remaining such interspaces the bosses of one wall bordering the interspaces being in abutting registering relationship with respect to the bosses of the other wall bordering said interspace, a substantial number of said abutted bosses having the engaged tops thereof secured together in top to top relationship.
